[57] CLAIM

The ornamental design for a lighting display stand assembly, as shown and described.

DESCRIPTION

FIG. 1 is a perspective view showing my new design;
FIG. 2 is a front view thereof;
FIG. 3 is a left end view thereof;
FIG. 4 is a right end view thereof;
FIG. 5 is a top view thereof;
FIG. 6 is a bottom view thereof;
FIG. 7 is a rear view thereof;
FIG. 8 is a front elevational view thereof on a reduced scale, the second lighting display stand assembly being shown in broken lines for illustrative purposes only; and,
FIG. 9 is an exploded view of the lighting display stand assembly showing the sections which compose the stand.
